UNITED STATES PATENT OFFICE.

HARLEY E. COGER, OF MINNEAPOLIS, MINNESOTA, AND JOHN B. MARSHALL, OF CHICAGO, ILLINOIS, ASSIGNORS TO SPEAR-MARSHALL COMPANY, OF CHICAGO, ILLINOIS, A CORPORATION OF DELAWARE.

THERAPEUTIC LAMP.

No. 938,950.

Specification of Letters Patent.

Patented Dec. 18, 1908.

Application filed August 31, 1905. Serial No. 278,848.

To all whom it may concern:

Be it known that we, HARLEY E. COGER, residing at Minneapolis, county of Hennepin, and State of Minnesota, and JOHN B. MARSHALL, residing at Chicago, in the county of Cook and State of Illinois, citizens of the United States, have invented new and useful Improvements in Therapeutic Lamps, of which the following is a specification.

10 This invention relates to a therapeutic lamp for therapeutically applying light-rays; and the object thereof is to set up a therapeutic lamp in a manner, as hereinafter described, which is particularly adapted to project the rays into portions of the human body such as the throat, ear, and nostrils.

15 The invention further aims to set up a therapeutic lamp in a manner as hereinafter described, with means to enable the escape of the surplus heat to prevent the parts of the lamp becoming intensely heated and at the same time preventing the luminous rays escaping from the lamp at a point other than the ray-outlet.

20 25 The invention further aims to set up a therapeutic lamp for the purpose set forth in a manner hereinafter described, with means whereby the lamp can be suspended at any desirable angle, as well as either vertically or horizontally.

30 35 The invention further aims to set up a therapeutic lamp which shall be simple in its construction, strong, durable, efficient in its use, and comparatively inexpensive to manufacture.

40 45 With the foregoing and other objects in view the invention consists of the novel construction, combination, and arrangement of parts hereinafter more specifically described, and illustrated in the accompanying drawings, wherein is shown the preferred embodiment of the invention; but it is to be understood that changes, variations, and modifications can be resorted to which come within the scope of the claims hereunto appended.

In the drawings, wherein like reference characters denote corresponding parts throughout the several views, Figure 1 is a vertical section of a therapeutic lamp in ac-

cordance with this invention. Fig. 2 is a 50 side elevation. Fig. 3 is a sectional plan. Fig. 4 is a detail showing the reflector and shield, and Fig. 5 is a sectional elevation showing in full lines a device for screening off certain of the rays from the illuminating means and in dotted lines other portions of the lamp.

Referring to the drawings by reference characters, 1 denotes the hood of the lamp, which is substantially conical in contour and has the apex thereof cut away to form a flanged opening 2. Said hood is further provided with a series of openings 2^a in the top thereof to permit of the surplus heat escaping. Connected to the bottom of the hood 1 is a 65 means to constitute a damper, which permits the surplus heat to escape, but is so constructed as to prevent the escape of the luminous rays. Said damper consists of a pair of annular members 3 4, each of said members 70 provided with openings 5, which when occasion requires are adapted to register with one another, so as to allow the escape of the surplus heat. The member 3 is fixed to the hood 1, while the member 4 is slidable upon 75 the member 3. The member 4 is arranged within the member 3 and is retained in position by the guide-lugs 6. The member 3 is provided with an elongated slot 7, through which extends a handle 8, which is fixed to the member 4. The slot 7 is adapted to limit the movement of the handle in either direction, so that when the handle is moved in one direction the openings will register with one another and when moved in the 80 opposite direction the openings will be closed. A suitable band 42 is provided which surrounds the damper so as to allow for the escape of the surplus heat, but at the same time prevents the escape of the luminous rays. 85 This band 32 is held in place, but away from the member 3, and is supported by studs 44, handle-plate 43, and the elliptical rod-plate 45. The band 42 is of sufficient breadth to more than cover the openings in the damper 90 and is held away by the studs 44 from the member 3 a sufficient distance to allow of free circulation of air.

Hinged to the member 3 is an inverted-cone-shaped director 9, which is retained in closure position through the medium of a spring-latch 10, attached to the member 3 and having its free end engaging the director 9. The function of the director 9 will be hereinafter referred to. The director 9 at its bottom is cut away so as to form a centrally-arranged opening 11 and is furthermore provided with an annular collar 12, and to the said collar 12, through the medium of a pin-and-slot connection 13, a conical-shaped cap 14 may be attached. Said cap 14 is provided with an opening 15, forming what is termed the "light-ray outlet."

Arranged within the hood 1 and suspended from the leading-in wires 16 is an illuminating and heating means 17 of great heat and light giving capacity, which may be an incandescent light or any other suitable means. By way of example, an incandescent lamp is shown, the socket holding the lamp being indicated by the reference character 18 and by which it is supported by means of the metal clips or clamps 18^a and the spiral spring 18^b and to which is connected through the medium of the binding-post 19 the leading-in wires 16. The socket 18 of the lamp extends through the opening 2 and carries a pair of vertically-extending screw-threaded rods 20, which project through a cap 21, said cap resting upon an annular flange 22, formed at the top of the hood 1. Thumb-screws 23 are provided for securing the cap to the socket 18, said thumb-screws being mounted upon the screw-threaded ends of the rods 20, said ends projecting outwardly from the cap 21. The leading-in wires 16 extend through three branches of a four-way coupling which is secured to the cap 21.

The branches of the four-way coupling are indicated by the reference characters 24, 25, 26, and 27. The leading-in wires extend through the branches 24, 25, and 26, and to the branch 27 is fixedly secured the upper end of a curvilinear suspension-rod 28. The lower end of said rod 28 is bent in an L-shaped manner, with the vertical portion of said L-shaped bend fixedly secured to the member 3, as at 29, while the upper end of the said rod 28 extends entirely over the four-way coupling, is then bent downwardly and outwardly curved, as at 29^a, and then bent downwardly in a vertical manner, as at 29^b, the end 29^b being fixed to the four-way coupling. The horizontal portion 29^c of the L-shaped bend at the lower end and the portions 29^a and 29^b at the upper end of the rod hold the rod 28 away from the hood 1. Upon the rod 28 is slidably mounted a hook-shaped connecting member 30, having a set-screw 31 for fixing said member 30 in its adjusted position. The portions 29^a, 29^b, and 29^c of the

rod enable the adjusting of the member 30 without it engaging the hood, and owing to the fact that the curvilinear portion 29^c is provided the member 30 can be adjusted to a position in vertical alignment with the four-way coupling, so that the lamp can be suspended vertically, and owing to the providing of the portion 29^c at the lower end of the rod the member 30 can be adjusted to abut against said portion 29^c, so that the lamp can be suspended horizontally. The adjusting of the member 30 to a position intermediate the portions 29^a and 29^c will enable the lamp to be suspended at any angle desired. Therefore the function of the rod 28 and member 30 is to permit the suspending or supporting of the lamp vertically or horizontally or at any angle desired. The illuminating and heating means is secured to the hood 1 by means of the socket and cap, which form a rigid connection with the flanged portion of the hood 1 when they are drawn together in place by thumb-screws 23 and the vertically-extending screw-threaded rods 20 and is connected directly to the leading-in wires, and the said rod 28 at its upper end is connected with the hood 1 through the medium of the rods 20 and the socket 18 and cap 21. The flange formed on the hood upon which the cap 21 bears is adapted to hold the cap and socket in their proper positions in relation to the hood.

Arranged within the hood 1 is a reflector 32, which is substantially concavo-convex in cross-section and provided with a centrally-arranged opening 33, through which extends the illuminating and heating means 17, said reflector 32 snugly fitting said means 17. Said reflector 32 is arranged within said hood 1 at a point below the openings 2^a, so that the inner face of the hood 1 below the reflector 32 will form a continuation of the reflector 32, said inner face of the hood 1 being highly polished. Extending upwardly from the reflector 32 is a conical-shaped shield 34, which surrounds the upper portion of the illuminating and heating means 17. The said shield 34 is connected to the reflector 32 through the medium of a plurality of aperture-l ears 35 and the nut-and-bolt connections 36. The reflector 32 is suspended within the hood 1 through the medium of a plurality of rods 37, which are secured at their lower ends through the medium of the nut-and-bolt connections 36 to the reflector, and at their upper ends are provided with hooks which engage the flange 22.

The director is provided with a suitable covering 38, so as to form an air-space 39, and said covering is provided with a ventilating-opening 40. The function of the covering air-space, and openings is to allow the escape of heat, so that the director can be

handled by the operator; otherwise the director would become very hot, and consequently could not be handled when occasion so required. The inner face of the director is highly polished, and the function of the director, together with its cap, is for the purpose of cutting off a certain amount of the rays and to also associate with the reflector 32, so as to enable the projecting of the light rays into portions of the human body, such as the throat, ear, and nostrils. The reflector 32 in the top of the hood associates with the director in such a manner that an approximate focal point is obtained near the apex of the lower cone.

The hood 1 is provided with a handle 41 for the convenience of the operator.

Arranged to be used with the hood 1 in place of the director 9 or with the director 9 is a series of circular frames, only one shown and which is indicated by the reference character 46, Fig. 5. The frame 46 is provided with either a flat or a concavo-convexed disk of colored glass, (the glass indicated by the reference character 46'), and the color thereof may be violet, blue, red, or any other desired color. The frame 46 is provided with a hinged section 47, so that the said section 47 can be detachably connected to the hinged section 48, carried by the damper. The frame 46 also carries a hinged section 49, so that the hinged section 50 of the director 9 can be detachably connected therewith. It may be well to state that the hinged section 50 of the director when the frame 46 is not used is connected to the hinged section 48. The frame 46 is also provided with a shoulder 51, so that the same can be engaged by the spring-catch 10, thereby retaining said frame in closure position with respect to the damper and hood. The frames 46, which are provided with the colored glass, are to be used in place of the director 9 for screening off certain of the rays from the illuminating means when desired to have only the colored light as indicated by the color of the glass.

We disclaim as joint inventors a therapeutic lamp consisting of a combined hood and director, an incandescent lamp of great heat and light giving power secured in the hood, and a reflector arranged in the hood and about the neck of the lamp; but neither one of us disclaims anything herein shown of which we may have been the sole inventor.

What we claim as joint inventors, and desire to secure by Letters Patent, is—

1. A therapeutic lamp comprising a hood, an illuminating and heating means arranged therein, a reflector associating with said means, an inverted-cone-shaped director associating with the reflector and said means and provided with a light-ray outlet,

a casing surrounding and connected to the director and provided with openings, and means for suspending the lamp at various angles.

2. A therapeutic lamp comprising a hood, an illuminating and heating means arranged therein, a reflector associating with said lamp, an inverted-cone-shaped director associating with the reflector and said means and provided with a light-ray outlet, and an adjustable damper for the surplus heat.

3. A therapeutic lamp comprising a hood, an illuminating and heating means arranged therein, a reflector associating with said lamp, an inverted-cone-shaped director associating with the reflector and said means and provided with a light-ray outlet, means for suspending the lamp at various angles, and an adjustable damper for the surplus heat.

4. A therapeutic lamp comprising a hood having openings for the escape of surplus heat, an illuminating and heating means arranged therein; a reflector associating with said means; a shield arranged within the hood and surrounding said means, a director associating with said means and reflector and having a light-ray outlet, and a damper interposed between said director and said hood.

5. A therapeutic lamp comprising a hood having openings for the escape of surplus heat, an illuminating and heating means arranged therein, a reflector associating with said means, a shield arranged within the hood and surrounding said means, a director associating with said means and reflector and having a light-ray outlet, a damper interposed between said director and said hood, and means for suspending the lamp at various angles.

6. A therapeutic lamp comprising a hood having openings for the escape of surplus heat, an illuminating and heating means arranged therein, a reflector associating with said means, a shield arranged within the hood and surrounding said means, a director associating with said means and reflector and having a light-ray outlet, a damper interposed between said director and said hood, and an elliptical-shaped supporting-rod connected at one end with said means and at its other end with said damper.

7. A therapeutic lamp comprising a hood, an illuminating and heating means arranged in the hood, a reflector within the hood and mounted in operative relation with respect to said means, a damper connected with the hood, and a frame suitably connected with the damper and carrying a colored glass.

8. A therapeutic lamp comprising a cone-shaped hood, an inverted-cone-shaped director suitably connected with said hood, form-

ing a continuation thereof and having a light-ray outlet, an illuminating and heating means arranged in said hood, and a damper arranged in operative relation with respect to 5 said hood and director.

9. A therapeutic lamp comprising a combined reflecting and directing device, illuminating and heating means arranged therein, a damping and ventilating device therefor 10 consisting of concentric perforated rings movable upon each other and located between the reflecting and directing devices.

10. A therapeutic lamp comprising a combined hood and reflector, a light-ray director 15 forming a continuation thereof, illuminating and heating means arranged within said hood and director, damping and ventilating means interposed between said hood and director and means for adjusting said damping 20 and ventilating means.

11. A therapeutic lamp comprising a combined hood and reflector, a director forming a continuation thereof and hinged thereto, illuminating and heating means arranged 25 within said hood and director, and means for suspending said hood at various angles comprising a curved rod extending from the apex of the hood to the lower edge thereof.

12. A therapeutic lamp comprising a combined hood and reflector, a light-ray director forming a continuation thereof, illuminating and heating means located within said hood and director, said director being made up of 30 two concentric separated parts, the outer 35 one of which is provided with perforations for the escape of heat.

13. A therapeutic lamp comprising an upper reflector and a lower director both conical in shape and hinged together at their bases, 40 an incandescent lamp of great heat and light capacity arranged in said hood, a reflector arranged in said hood and about the neck of said lamp, a damper located between the hood and director, and a light-ray outlet for 45 said director.

14. A therapeutic lamp comprising an upper conical hood and a lower conical director hinged together at their bases, a reflector located in and constituting with the lower inner surface of said hood an enlarged reflector, 50 illuminating and heating means of great capacity arranged in said reflector, a damper interposed between the hood and the director and a light-ray outlet for the lower conical director.

15. A therapeutic lamp comprising a hood, an incandescent lamp of great heat and light giving capacity arranged in said hood, a reflector within the hood and surrounding the 55 neck of the lamp, and one or more frames suitably connected with the hood and carrying a colored glass.

16. A therapeutic lamp comprising a hood, an illuminating and heating means arranged therein and extending through the top thereof, a director connected to the hood and forming a continuation thereof and having a light-ray-outlet cover, a curvilinear suspension-rod connected to the hood and extending from one end to the other end thereof, a 65 connecting member slidably mounted on said rod, a casing surrounding said director suitably connected therewith and provided with outlets and a damper connected to the hood. 70

17. A therapeutic lamp comprising a combined reflecting and directing device, illuminating and heating means arranged therein and a damping and ventilating device therefor 75 consisting of concentric perforated rings movable upon each other and connected 80 to said device.

18. A therapeutic lamp comprising a combined hood and reflector, a director forming a continuation thereof and hinged thereto, illuminating and heating means arranged 85 within said hood and director, and means for suspending said hood at various angles comprising a rod extending from the apex of the hood to the lower end thereof.

19. In a therapeutic lamp, a combined 90 hood and director, an incandescent lamp of great heat and light giving power secured in said hood, said director provided with means for controlling the light-rays so they can be directed through an opening for internal 95 treatment in the mouth and throat, a reflector arranged in the hood and about the neck of the lamp, the reflector, hood and director forming a continuous reflecting-surface, and means for flexibly suspending said lamp. 100

20. In a therapeutic lamp, a combined hood and director, the latter having an outlet for controlling the light-rays, an incandescent lamp of great heat and light giving power secured in the apex of said hood, a reflector arranged in the hood and about the 105 neck of the lamp, the reflector, hood and director forming a continuous reflecting-surface and means for flexibly suspending said lamp. 110

21. A therapeutic lamp comprising a combined hood and reflector, a director forming a continuation thereof and suitably attached thereto, illuminating and heating means arranged within said hood and director, and means for suspending said hood at various 115 angles comprising a rod extending from the apex of the hood to the lower end thereof.

22. A therapeutic lamp comprising a combined hood and reflector, illuminating and heating means arranged within said hood, and means for suspending said hood at various angles comprising a curved rod having its lower portion bent at an angle with respect 120

to the hood and secured thereto and its upper portion bent downwardly upon an outward curve and secured to the apex of the hood, and an adjustable connecting member 5 slidably mounted upon said rod, said depending portion and said angular portion respectively at the top and bottom of the rod holding the rod away from the hood and said curved depending portion at the top of the 10 rod enabling the positioning of the connecting member in vertical alinement with the apex of the hood.

Correction in Letters Patent No. 838,950.

It is hereby certified that in Letters Patent No. 838,950, granted December 18, 1906, upon the application of Harley E. Coger, of Minneapolis, Minnesota, and John B. Marshall, of Chicago, Illinois, for an improvement in "Therapeutic Lamps," an error appears in the printed specification requiring correction, as follows: In line 55, page 3, the pronoun "we" should read *he*; and that the said Letters Patent should be read with this correction therein that the same may conform to the record of the case in the Patent Office.

Signed and sealed this 15th day of January, A. D., 1907.

[SEAL.]

F. I. ALLEN,
Commissioner of Patents.
